US00D684559S

(12) **United States Design Patent**
Groset et al.

(10) **Patent No.:** **US D684,559 S**
(45) **Date of Patent:** **** Jun. 18, 2013**

(54) **ZIPPERED HEADPHONE**

(75) Inventors: **Erik Groset**, Carlsbad, CA (US); **Justin Liu**, San Diego, CA (US); **Michael Klasco**, Richmond, CA (US); **Robin DeFay**, Poway, CA (US)

(73) Assignee: **Zipbuds, LLC**, San Diego, CA (US)

(**) Term: **14 Years**

(21) Appl. No.: **29/416,058**

(22) Filed: **Mar. 16, 2012**

Related U.S. Application Data

(63) Continuation-in-part of application No. 13/289,830, filed on Nov. 4, 2011, which is a continuation-in-part of application No. 12/941,943, filed on Nov. 8, 2010.

(57) **CLAIM**

The ornamental design for a zippered headphone, as shown and described.

DESCRIPTION

FIG. 1 is a front perspective view of zippered headphones showing our new design, the opposite perspective view is a mirror image, the cord is drawn broken away for indeterminate length;

FIG. 2 is a front view thereof;

FIG. 3 is a back side view thereof;

FIG. 4 is a side view thereof;

FIG. 5 is a top view thereof; and,

FIG. 6 is a bottom view thereof.

The broken lines shown in the drawing disclosure are for illustrative purposes only, and form no part of the claimed design.

1 Claim, 6 Drawing Sheets
